Primary Examiner — Garth Rademaker*Assistant Examiner* — Kristy N. Nilsson(74) *Attorney, Agent, or Firm* — Foley & Lardner LLP(57) **CLAIM**

The ornamental design for a steering wheel as shown and described.

DESCRIPTION

FIG. 1 is a first front perspective view of a first embodiment of a steering wheel showing our new design;

FIG. 2 is a second front perspective view thereof;

FIG. 3 is a front view thereof;

FIG. 4 is a rear view thereof;

FIG. 5 is a first side view thereof;

FIG. 6 is a second side view thereof;

FIG. 7 is a top view thereof;

FIG. 8 is a bottom view thereof;

FIG. 9 is a first front perspective view of a second embodiment of a steering wheel showing our new design;

FIG. 10 is a second front perspective view thereof;

FIG. 11 is a front view thereof;

FIG. 12 is a rear view thereof;

FIG. 13 is a first side view thereof;

FIG. 14 is a second side view thereof;

FIG. 15 is a top view thereof; and,

FIG. 16 is a bottom view thereof.

The broken lines shown in the drawings illustrate portions of a steering wheel that form no part of the claimed design.
